The ornamental design for a hanging storage bag as shown and described.

DESCRIPTION

FIG. 1 is a front perspective view of a hanging storage bag showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 of FIG. 1.

The broken line portions of the file organizer in FIGS. 1-9 represent unclaimed portions of the hanging storage bag and form no part of the claimed design. The dot-dot-dash broken lines in FIGS. 1 and 9 depict the unclaimed boundary of the enlarged detail view.
